(57) CLAIM

The ornamental design for a hookah, as shown and described.

DESCRIPTION

FIG. 1 is a top perspective view of the hookah, showing my new design;

FIG. 2 is a front elevation view thereof;

FIG. 3 is a right-side elevation view thereof;

FIG. 4 is a rear elevation view thereof;

FIG. 5 is a left side elevation view thereof;

FIG. 6 is a top plan view thereof;

FIG. 7 is a bottom view thereof; and,

FIG. 8 is a front perspective view of the hookah shown in a configuration of use.

The broken lines depict portions of the hookah that form no part of the claimed design.
